UNITED STATES PATENT OFFICE.

PEYTON LEON HOWLETT, OF BROWNWOOD, TEXAS.

BATHING-MACHINE.

1,192,314.

Specification of Letters Patent. Patented July 25, 1916.

Application filed April 23, 1915. Serial No. 23,362.

To all whom it may concern:

Be it known that I, PEYTON LEON HOWLETT, a citizen of the United States, residing at Brownwood, in the county of Brown, 5 State of Texas, have invented certain new and useful Improvements in Bathing-Machines, of which the following is a specification.

This invention relates to a bathing apparatus embodying a cabinet, or the like, 10 which is adapted to be occupied by a person, and which in the preferred form, embodies a plurality of scrubbing elements, so mounted and disposed within the cabinet that 15 they are adapted to surround a person when occupying the cabinet. While the cabinet, which will be hereinafter further described, may be of any suitable construction, it is 20 illustrated as being cylindrical, and constructed of metal, and while the scrubbing elements, which will be hereinafter described, are illustrated as brushes, they may 25 be constructed of any other suitable material.

Other details of construction set forth in the accompanying drawings are selected for 30 purposes of illustration, and while, in themselves, embracing some of the minor features of the invention, they are not to be taken as limiting the scope of the invention.

One object of the invention is to provide a bathing apparatus with means for imparting scrubbing motion to the scrubbing brushes, and means for varying the speed 35 of the brushes at will, to which end, the invention embodies a cabinet having mounted therein a plurality of scrubbing brushes and driving means connecting said brushes with any suitable source of power that may be 40 conveniently available, such for instance as a hydraulic motor operated by the pressure of an available water supply, a line-shaft, the axle of a railway car, or an electric motor, which motor, in order to vary the speed 45 of the brushes, will be in circuit with a suitable variable rheostat, or the like, whereas the other forms of prime mover will be provided with equivalent means for varying the 50 application of power to modify at will the speed at which the brushes are driven.

Therefore, when the electric motor or its controlling rheostat are hereinafter referred to in the specification or claims, they are to be regarded as not limiting the features of 55 the invention to use in connection with this particular type of prime mover and controlling means, but as intending to embrace in scope, any type of prime mover and regulating means known to be suitable for the 60 purpose.

Another object of the invention is to produce an apparatus which may be readily used as a massaging and drying device, as well as a bathing device, to which end the 65 apparatus is provided with suitable water circulating connections which are readily controlled by a person occupying the cabinet, whereby the apparatus may be supplied with water for bathing purposes, and the 70 water cut off when it is desirable to employ the device as a massaging means for stimulating the body or for drying the body after the bath.

Another object of the invention is to so 75 regulate the water circulation with respect to the scrubbing brushes, that the body of the person occupying the cabinet will be well supplied with water, at a very much less expenditure of water than in the use of the 80 ordinary shower bath; hence the apparatus can be installed on railway trains or other places where water supply is limited, and in this connection it is to be noted that by reason of central delivery and radial discharge of the water through the brushes, 85 the latter will be kept in sanitary condition at all times. The centrifugal force developed by rotation of the brushes not only assists in keeping the brushes flushed and 90 cleansed while the water is flowing, but renders them self-drying after the water is shut off.

Further objects relate to the details of construction and coöperative relationship of 95 the device, whereby its broader characteristics are embodied in a structure that is conveniently operated, comparatively simple in design, and very durable in use, to the end that the device may be employed in 100 places where other bathing apparatuses would be found to be impracticable, as for

instance, in railroad trains, where the floor space is limited. In order that the device may be employed to accommodate persons of different sizes, some of the brushes are 5 so mounted that they may swing in an arc, and thereby increase or decrease the circumferential dimensions of the space which is occupied by a person in the cabinet. The device is also provided with means for disposing of the waste water and lather which 10 is thrown off during the bathing process.

The invention will be more fully understood from reference to the accompanying drawings, in which—

15 Figure 1 is a side elevation of the complete apparatus; Fig. 2 is a side view of the apparatus showing the cabinet open and ready to be occupied by a person; Fig. 3 is a top plan view of the apparatus; Fig. 4 is a transverse section on the line 4—4, Fig. 2; Fig. 5 is a vertical section looking at the front of the apparatus; Fig. 6 is a sectional view looking at the side of the apparatus; Fig. 7 is an enlarged detail view with parts broken away, of one of the scrubbing brushes. Fig. 8 is a transverse section on the line 8—8, Fig. 1.

Referring to the drawings in detail, 1 represents a cabinet which may be constructed of any suitable material, preferably 30 some kind of metal, and in order to render it accessible it is constructed of two halves hinged together at 1^a and adapted to swing into and out of closed position, and in order 35 to retain the two halves in closed position, a suitable catch 2 is employed. Mounted with freedom of rotation in the cabinet 1 are a plurality of vertically disposed scrubbing brushes 3, two or more of which, such 40 as 3^a are preferably pivotally mounted to enable them to swing in an arc when the cabinet is opened, and in this way enable a person to readily occupy the cabinet, as well as to increase or decrease the circumferential dimension of that part of the apparatus 45 occupied by a person. The cabinet is supported on the base 4 by the hinge 1^a. The base comprises a basin 5 and a drip flange 6, each of which is above the base and extending outwardly therefrom in step formation. The drip flange 6 is constructed with 50 an annular up-turned portion 7 and provides a pan for catching the excess of water which may drip down the outer side of the cabinet. The base 4 is further provided with an axial bearing 8 on which is mounted and keyed a driving disk 9 which is provided with a bevel face 10 by which the bevel gears 11 of the brush shaft 12 are 55 adapted to be driven, thereby rotating their respective brushes. The disk is further provided with a longitudinal friction face 13 on which a friction roller 14 is mounted with freedom of rotation, which roller contacts with the disks 15 on the brush shafts 60

16 of the brushes 3^a and imparts a rotary motion thereto. By means of the brushes being rotated by an independent friction gear on each brush shaft coating with the single driving gear, any brush may be arrested without interrupting the remaining brushes. This is particularly advantageous should a woman have her hair caught or wound around any of the brushes. In order 70 to transmit motion to the driving disk 9 and thus impart the desired rotary motion to the scrubbing brushes, the same is provided on its under side with teeth 17 which mesh with a suitable toothed pinion 18 mounted on the shaft 19 of the motor 20, which shaft 80 enters the basin through the stuffing box 21. Mounted in the basin 5 coaxially with the driving disk 9, is a stand 22 for supporting a person when occupying the cabinet. This stand is rendered adjustable, for persons of 85 different height, by means of its screw-threaded shank 23 extending through the axis of the bearing 8.

24 represents a drain connection for draining the basin 5 of water.

Again referring to the brushes 3 and 3^a, it is to be seen that they are braced at their tops and bottoms by means of the brackets 26 and 27 to retain them in frictional contact with the driving disk. Each brush is 95 provided with a hollow core 28 (see Fig. 7) with perforations 29 extending into the brush structure, and with the hollow shaft 30 connecting with leads 31 of the water connection 32, the brushes are supplied with 100 water from a suitable supply pipe 33 which is connected to the water connection by the lead 33^a. The supply pipe 33 is provided with two valves 34 and 35, one of which controls the hot water supply, and the other, 105 the cold water supply. As heretofore stated, with respect to the brushes 3^a, they are mounted free to swing in and out, and in order that they may act in this capacity, they are mounted at their bottoms by separate brackets 36 which are pivoted to the bracket 26 at 26^a, and at their tops by their water connections 31 which include hinge-joints 37. When thus mounted, they 110 may be readily swung in and out at will.

115 38 represents a variable rheostat for varying the speed of the motor 20, and the scrubbing brushes driven thereby. This rheostat may be mounted at any convenient location where it will be in reach of the person when occupying the cabinet.

120 From the foregoing description it will be seen that a person wishing to take a bath may turn on the water in a manner to secure the desired temperature, when he may occupy the cabinet and start the brushes rotating by cutting in the electric motor. As above stated, the rheostat 38 is in convenient position to be controlled by the person when occupying the cabinet and thereby enable 125 130

him to control the rotation of the scrubbing brushes. After the bathing process is completed the water may be cut off and the brushes used to dry, as well as to massage the body.

I claim:—

1. In combination with a bathing apparatus, of an annular series of vertically disposed rotary brushes, each having at one end a driven gear, and a common driving gear concentric with the annular series of brushes and in driving relation to all of said driven gears.

2. In combination with a bathing apparatus, of an annular series of vertically disposed rotary brushes, each having at one end a driven gear, and a common driving gear concentric with the annular series of brushes and in driving relation to all of said driven gears; said gears having frictional driving surfaces whereby any brush may be arrested, without interrupting the remaining brushes.

3. In combination with a bathing apparatus, of an annular series of vertically disposed rotary brushes, each having at one end a driven gear, and a common driving gear concentric with the annular series of brushes and in driving relation to all of said driven gears; said gears co-acting through the medium of friction faces and the driving gear having another face, constructed to coact with a power-transmitting element.

35. 4. In a bathing apparatus, an annular series of vertically disposed rotary brushes adapted to surround the body of the user, and a mounting for said brushes comprising a water pipe with radially presented branch pipes, each having a bearing in which a brush rotates and through which water is supplied to the brush.

5. In a bathing apparatus, an annular series of vertically disposed rotary brushes adapted to surround the body of the user, and a mounting for said brushes comprising a water pipe with radially presented branch pipes, each having a bearing in which a brush rotates and through which water is supplied to the brush; said water pipe being in annular form and said branch pipes being extended inwardly therefrom.

6. In an apparatus of the character described, a scrubbing element comprising an annular series of vertically disposed rotary brushes adapted to surround the body of the user, a mounting for said scrubbing element sustaining and presenting it in position to receive the body of the user when standing erect, a substantially cylindrical shield surrounding the series of scrubbing brushes and means for supplying a fluid at the scrubbing surfaces of the scrubbing elements, additional brushes being adapted to enter said annular series but movable out-

ward therefrom to admit the user, and separate driving connections for said movable brushes maintaining driving connection therewith in the different positions of said brushes.

70

7. In an apparatus of the character described, a scrubbing element comprising an annular series of vertically disposed rotary brushes adapted to surround the body of the user, a mounting for said scrubbing element sustaining and presenting it in position to receive the body of the user when standing erect, a substantially cylindrical shield surrounding the series of scrubbing brushes and means for supplying a fluid at the scrubbing surfaces of the scrubbing elements; a common driving gear having an upwardly presented beveled driving face, and brush gears having downwardly presented beveled driving faces coacting therewith and resting thereon by the weight of the brushes.

75

8. In an apparatus of the character described, a scrubbing element, a mounting for said scrubbing element sustaining and presenting it in form and position to receive and surround the body of the user when presented against the scrubbing element, and means for developing scrubbing movement in said scrubbing element, a shield surrounding the scrubbing element and constructed of relatively movable sections adapted to separate, and open the shield to admit the user to the presence of the scrubbing element; and means for supplying a fluid at the scrubbing surface of the scrubbing element; said scrubbing element comprising a plurality of scrubbing members, some of which are movable to admit the user within the scrubbing element; the movable shield sections having connections through which they control the movable scrubbing members.

80

9. In an apparatus of the character described, a scrubbing element, a mounting for said scrubbing element sustaining and presenting it in form and position to receive and surround the body of the user when presented against the scrubbing element, and means for developing scrubbing movement in said scrubbing element, a shield surrounding the scrubbing element and constructed of relatively movable sections adapted to separate, and open the shield to admit the user to the presence of the scrubbing element; and means for supplying a fluid at the scrubbing surfaces of the scrubbing element; said scrubbing element comprising a plurality of scrubbing members, some of which are movable to admit the user within the scrubbing element; the movable shield sections having resilient connections through which they yieldingly control the movable scrubbing members.

85

10. In a bathing apparatus, an annular

series of vertically disposed rotary brushes adapted to surround the body of the user, a substantially cylindrical shield surrounding said annular series of brushes and divided and mounted for opening to admit the user within the annulus, and a drip pan beneath the brushes and shield; said drip pan having an annular extension provided with a confining flange over which

the opening and closing movements of the shield take place.

The foregoing specification signed at Brownwood, Texas, this 20th day of April, 1905.

PEYTON LEON HOWLETT.
